DESIGN FOR A PIANO CASE

William Zaiser, Rockville Centre, N. Y., assignor to Steinway & Sons, New York, N. Y., a corporation of New York

Application February 19, 1937, Serial No. 67,734

Term of patent 7 years

To all whom it may concern:

Be it known that I, William Zaiser, a citizen of the United States of America and a resident of Rockville Centre, L. I., county of Nassau, and State of New York, have invented a new,
original, and ornamental Design for a Piano
Case, of which the following is a specification, reference being had to the accompanying drawing, forming part thereof:—

Figure 1 is a top plan view of the piano case,
showing my new design;

Figure 2 is a front view;
Figure 3 is a side view thereof; and Figure 4 is a sectional view taken on line 4—4
of Figure 2.

I claim:—
The ornamental design for a piano case, as shown.

WILLIAM ZAISER.
